UNITED STATES PATENT OFFICE.

CARL C. HARRIS, OF ORANGE, MASSACHUSETTS.

OPEN FILE.

Application filed May 4, 1927. Serial No. 188,799.

This invention relates to a device for filing letters or other papers and is particularly adapted for use as a daily file or a temporary reminder for papers, folders, and the like, which require attention at short intervals, rather than as a permanent file. It can be used for the latter purpose however.

The principal objects of the invention are to provide a file which can be used on a desk or table in horizontal position or can be put way in a deep drawer in vertical position or used in vertical position as desired; to provide a construction in which the head ends of the letters or folders will project outwardly at the front and the separating tabs on the division sheets will also project out beyond them, where they will be readily accessible at all times and visible without disturbing them; to provide a construction in which the different kinds of papers are separated from each other at their visible ends only so that they can be withdrawn very readily and in which the letter folders that are used will be held loosely at their outer ends for the last-mentioned purpose; also to provide a mechanical device by which the letters or folders can be further separated when they are to be inspected so that they can be identified more easily and taken out with more facility; to provide a practical file which can be used on the table or desk and then put away in the drawer on end if desired, all ready for use again; to provide means for connecting two or more of the files together or stacking them up one on the other, such means preferably being of such a nature that the files are connected together immovably as long as the connecting means is in position; to provide means, preferably associated with the last named means, for holding down the inner ends of the folders and papers within the box or file; to provide separating bars at the front of the file which preferably have some resilience, so that a particularly thick bunch of papers can be inserted and held and removed with just as much readiness as if the space were not all filled; and to provide simple means for holding the files together at their front or open ends, especially when they are to be put away in vertical position.

Other objects and advantages of the invention will appear hereinafter.

Reference is to be had to the accompanying drawings in which

Fig. 1 is a perspective view of one of the

file boxes with a preferred embodiment of this invention shown therein;

Fig. 2 is a longitudinal sectional view of the same showing the devices inside in elevation and folders in position;

Fig. 3 is a plan of the same with the folders in position so as to conceal practically all of the separating bars except the top one;

Fig. 4 is a view similar to Fig. 2 showing the device opened up and the folders separated;

Fig. 5 is a sectional view showing the means for connecting two or more of the boxes together when they are stacked up, one over the other;

Fig. 6 is a view similar to Fig. 1 showing a simplified form of the invention;

Fig. 7 is a front view thereof with one of the spaces crowded with papers showing the utility of the yielding form of separating bars;

Fig. 8 is a similar view showing a more complete means for holding the boxes in vertical, instead of horizontal, position;

Fig. 9 is an end view of the arrangement shown in Fig. 8 illustrating the means for holding the boxes together at the top; and

Fig. 10 is a fragmentary plan thereof especially showing these holding clips at the top.

In the form shown in the first five figures, the invention is shown as comprising a filing box 10 which I will sometimes refer to as a file. This is a rectangular box having sides and a rear wall but open at the front. The distance from the rear wall to the front is less than the length of the folders 11 which are placed in the file so that the front ends of the folders or papers, and especially the tabs 12 thereon, which designate them, project out and are readily visible at the front. The folders are separated by a series of cross bars 13 which, in this form, are shown as movably mounted on a pair of frames 14. These frames are pivoted on a cross bar 15 which in all respects is similar to one of the bars 13 except that it extends clear through the side walls and thus constitutes a pivot for the two frames 14 which support the bars 13. The lower folder or series of papers 11 will rest on this bar 15 and thus will be in the same position irrespective of the position of the other bars.

The folders are put into the file in the positions indicated in Fig. 2 where they do not

project above the top of the file. If they do the placing of another file upon it is not hampered. The frames 14 project upwardly to the top of the side walls and I have shown them projecting above them. When the device is to be used stacked up, one file over another, this frame will not be made long enough to project above the side walls when in the filing position shown in Fig. 2.

10 When it is desired to withdraw a folder or paper, one of these ends is tilted forward. This moves the frames up to the position shown in Fig. 4. I have illustrated no mechanical means for holding the frames in that position as ordinarily the papers themselves will hold it there. Of course such a means could be provided in a very simple way. It will be seen that in this position the folders are quite widely separated at the front end so 20 that the visibility and accessibility of the device is enhanced. One of these folders can be removed and replaced, either in its original position or elsewhere, with extreme facility and without danger of dislodging another 25 one.

It will be noted that, as the folders are separated at the front, they will not occupy as much space in the rear as they do in the front. It is convenient also to provide means 30 to prevent their rising upwardly in the rear and thus prevent disarranging the papers and possibly allowing the top one to be accidentally removed. For this purpose I provide a pair of metal clips 17 each having a projection 18. They are secured to the rear wall of the file by a screw 19 or other holding device and they can be used for the purpose specified ordinarily. If it is desired to use them for the purpose of providing an upwardly extending projection to enter the next file above, for stacking the files one over another horizontally, they can be reversed as shown in Fig. 5, which shows a slight modification. Here these clips are longer than those shown 45 in the first four figures and they pass through holes 20 in the bottoms of the files next above to prevent dislocation of the files.

In the form shown in Figs. 6 and 7, the bars 50 23 are of a length sufficient to pass through or into holes in the front ends of the side walls and are stationary. In this case they serve the same purpose as they would in Fig. 2 if they were not to be moved. They separate the papers and leave the tabs visible but 55 they cannot be moved to provide any further separation. They do not allow for filing quite as bulky folders as the form shown in the first four figures. In this case and in the other cases also if desired, the rods are made 60 of small cylindrical wooden strips, or they may be made in any other shape. They are longer than the width of the papers filed so that the resiliency of the rods can be employed to pack thick bunches of papers between them as indicated at the top of Fig. 6.

Of course they can be made of metal wires if desired and can consist of pins projecting in from each side.

I have already described the clips 17 shown in Fig. 5 and their two features of utility. 70 In Fig. 8 I have shown an addition to this which consists in employing clips 27 fastened in the same way as in the previous figures and each provided with a perforation 28. A tack or nail 29 is inserted through it into the end 75 of the next file when they are stacked up together in vertical position so as to hold them there for use in vertical filing and especially for use in putting them away for a period in a deep drawer or the like. When this is 80 done, it is also preferable to connect the rods 23 in these files by spring clips 30 at both ends. This holds the files together at the top and bottom for vertical filing as will be 85 obvious from Figs. 9 and 10.

By this invention, in each of the forms shown, a convenient way of filing papers and folders is provided and one in which the indicating tabs provide instant visibility. The papers are loose at their front ends to increase 90 this advantage. The user does not have to see the tabs and does not run the risk of disarranging the papers for that purpose. The papers can be further separated by using the form shown in the first four figures without 95 adding very materially to the expense of the device. The files are arranged so that they can be stacked up, one on the other, in horizontal position and so that they can be used in vertical position, as shown in the last three 100 figures, and filed away in that position very conveniently. It is a very simple arrangement and very flexible and is particularly adapted for files which are in frequent use.

Although I have illustrated and described 105 several forms of the invention, I am aware of the fact that modifications can be made therein by any person skilled in the art without departing from the scope of the invention as expressed in the claims.

Therefore, I do not wish to be limited to all the details of construction herein shown and described, but what I do claim is:—

1. As an article of manufacture, a file for the purpose described comprising a horizontal tray-like structure having an open front, a series of horizontal members spaced apart and located at the front for supporting and separating different folders and papers, said papers or folders lying in contact with each other at the rear and separated from each other by the members at the front, whereby they are instantly visible and readily separable.

2. As an article of manufacture, a file for the purpose described having an open front end and a series of separating members at the front of the file in a position to support the papers with the indicating ends of the papers projecting in front of the members,

and horizontal means at the rear for holding the rear ends of all the folders or papers down in the file.

3. As an article of manufacture, a file for 5 the purpose described comprising a box having an open front, a series of bars spaced apart and extending across the front for supporting and separating different folders and papers at the front, and a pair of clips at the 10 rear of the file having forward projections to hold all the papers in the file at their rear ends horizontal.

4. As an article of manufacture, a file for 15 the purpose described comprising a box having an open front, a series of bars spaced apart and extending across the front for supporting and separating different folders and papers, and a pair of clips at the rear of the 20 file having forward projections to hold the papers in the file at their rear ends, said clips being reversible to project upwardly from the rear wall of the file for the purpose of holding two files together.

5. In a file for the purpose described, the combination with a box open at the front end, 25 of a pair of frames pivoted to the box near the front end, each frame having two arms at an angle to each other, a series of rods extending across the box and carried by one of said arms for separating the papers, the other 30 arms serving as levers for swinging the frames about their pivots so as to raise the rods into a more nearly vertical position and separate the front ends of the papers.

6. In a file for the purpose described, the 35 combination with a box, of a frame pivoted to the box near the end, a series of rods extending across the box and carried by said frame for separating the papers, means for swinging the frame about its pivots so as to 40 raise the rods into a more nearly vertical position and separate the front ends of the papers.

In testimony whereof I have hereunto affixed my signature.

CARL C. HARRIS.
